GAUGING APPARATUS FOR BUILDERS
AND THE LIKE

Richard Eggemeyer, Walsh, Ill.

Application August 11, 1943, Serial No. 498,236

3 Claims. (Cl. 33—174)

My invention relates to improvements in gauging apparatus for use by builders, carpenters, masons, and the like, in erecting cylindrical tower-like structures, particularly silos.

The principal object of my invention is to provide simply constructed, inexpensive apparatus which may be quickly and easily erected for convenient use to gauge the inside diameter of silos and like structures by progressive steps, upwardly, as the structures are erected, so that the walls may be built up symmetrically and perpendicularly, or inwardly inclined, as desired, and which is adapted to be easily taken apart for storage, transportation, or other similar purposes.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in top plan illustrating my improved gauging apparatus installed.

Figure 2 is a view partly in vertical section and partly in side elevation and drawn to an enlarged scale.

Figure 3 is a view in perspective of the gauging arm, the mounting therefor, and the gauging finger,

Figure 4 is a view in side elevation of a portion of the gauging arm and the gauging finger drawn to an enlarged scale,

Figure 5 is a detail view in vertical section taken on the line 5—5 of Figure 2,

Figure 6 is a view in perspective of one of the posts and bracing means therefor,

Figure 7 is a detail view in vertical section taken on the line 7—7 of Figure 2,

Figure 8 is a view in longitudinal section taken on the line 8—8 of Figure 2 and drawn to a further enlarged scale,

Figure 9 is a view in transverse section taken on the line 9—9 of Figure 2 and drawn to an enlarged scale, and

Figure 10 is a view in perspective of parts of one of the guy members.

Referring to the drawings by numerals, my improved gauging apparatus has been illustrated therein, by way of exemplification of a preferred practice of the invention, as erected on the circular floor 1 of the usual silo, the circular block wall 2 of which, as shown in part, is constructed of the usual concrete blocks 3 laid in break joint rows.

The basic element of my improved gauging apparatus comprises a center pole, or mast, 4 of tubular form which, preferably, is formed of pipe sections 5 detachably connected by the usual threaded couplings 6. The sections 5 are provided with end apertures 8 therein forming tool holds for use in coupling the sections 5 together by means of a suitable tool. The pole 4 is designed to be erected to a height substantially greater than the contemplated height of the silo, and the uppermost section 5 is provided with a cap flange 9 for the attachment of guy members 10 thereto. The pole 4 is centered in the floor 1 by means of a tubular plug 10' suitably wedged into a center hole 11 provided in said floor, the plug fitting into one end of the lowermost pipe section 5.

The guy members 10 comprise cables 12 suitably attached, as at 13, to the cap flange 9 and connected at their lower ends by adjustable loops 14 to chain sections 15 adapted to be connected to flat hooks 16 suitably attached, as at 17, to the tops of short posts 18 driven into the ground around the silo location in substantially 90 degree angular relation around the same, and approximately equidistantly spaced apart and from the center of the floor 1. The posts 18 may be suitably braced, as at 19. The loops 14 are rendered adjustable by suitable clamps 14'. The pole 4 may be set exactly vertical with the aid of the usual plumb bob, not shown, and the guy members 10 tightened to maintain the pole in place.

A pair of upper and lower, extensible brace bars 20, 21 are provided for bracing the pole against bending and maintaining the same in the axis of the silo as the structure is built up. The bars 20, 21 extend diametrically of the pole, and the wall 2, and each comprises a center section 22 adapted to be secured to the pole by a clip 23 and bolts 24, and a pair of end sections 25 endwise slidable on the center section into set positions in which said sections engage the inner face of the wall 2. Guide clips 26 on the sections 22 slidably mount the end sections 25 on the center sections and longitudinal slots 27 in the end sections, together with bolts 28 on the center sections 22, provide for setting the latter. As will be clear, the bars 20, 21 are vertically adjustable on the pole 4 in selected set positions by means of clips 23 and bolts 24, so that said bars may be slid upwardly on the pole 4 into selected positions as the wall 2 rises. Also, said bars 20, 21 are rotatably adjustable about the

pole 4 to dispose the same in cross relation for purposes which will be apparent.

A gauge arm 29 is mounted on the pole 4 above the bars 20, 21 to extend laterally therefrom for radius and diameter gauging, said arm being swingably mounted to describe a circle around the pole, and endwise adjustable for establishing different diameters and radii for different sizes of silos. The mounting for the gauge arm 29 comprises a U-shaped yoke 30 terminating in oppositely turned hooks 31 designed to rotatably fit the pole 4, and a cross-arm 32 on said yoke. The gauge arm 29 slidably extends through horizontally aligned clips 33 on the yoke 30 and on the cross-arm 32, respectively. On the gauge arm 29 is an outer end section 34 hinged thereto, as at 34', to swing in one direction about a vertical axis when the silo wall 2 is out of round, and also for folding to shorten the gauge arm when desired. A vertical gauge finger 35 is pivoted, as at 36, to the outer end of the section 34 for swinging adjustment on the finger 35 into vertical or different inclined positions established by a set screw 36 in said finger, and an arcuate slot 37 in said section 34. The gauge finger 35, when vertical, forms a straight edge for wiping against rows of blocks 3 to determine when the same are properly set, or for bearing against a block in one row to form a guide for laying a block in a higher row. As will be understood, the gauge arm 29 may be slidably set in the clips 33, 34 for different diameter and radius gauging operations.

A slideable clip 36 is provided on the pole 4 beneath the yoke 30 for supporting the yoke and which is designed for vertical adjustment along the pole 4 to sustain the yoke and arm 29 at different levels. The clip 36 may be of any suitable construction adapted for tightening around the pole 4, or loosening, by manipulation of bolts 37.

The foregoing will, it is believed, suffice to impart a clear understanding of my invention, since the use of the apparatus and parts has been set forth in connection with the description of the structure thereof.

Manifestly, the invention, as described, is susceptible of modification without departing from the inventive concept, and right is herein reserved to such modifications as fall within the scope of the appended claims.

What I claim is:

1. In apparatus for use in erecting a circular wall, a pole adapted to be arranged in upright position in the axis of said wall, a U-shaped yoke extending laterally from said pole and having ends rotatably and slidably mounted on said pole, an upright brace bar fixed to the yoke, a gauge arm adapted to extend horizontally from said yoke and having an inner end portion slidably mounted on said yoke and brace bar, respectively, a straight edge finger, and means to mount said finger on said gauge arm at the outer end thereof in upright position and for lateral swinging movement about an axis perpendicular to the axis of said gauge arm.
2. In apparatus for use in erecting a circular wall, a pole adapted to be arranged in upright position in the axis of said wall, a U-shaped yoke extending laterally from said pole and having ends rotatably and slidably mounted on said pole, an upright brace bar fixed to the yoke, a gauge arm adapted to extend horizontally from said yoke and having an inner end portion slidably mounted on said yoke and brace bar, respectively, a straight edge finger, and means to mount said finger on said gauge arm at the outer end thereof in upright position and for lateral swinging movement about an axis perpendicular to the axis of said gauge arm, comprising an outer end section on said gauge arm hinged to said arm.
3. In apparatus for use in erecting a circular wall, a pole adapted to be arranged in upright position in the axis of said wall, a U-shaped yoke extending laterally from said pole and having ends rotatably and slidably mounted on said pole, an upright brace bar fixed to the yoke, a gauge arm adapted to extend horizontally from said yoke and having an inner end portion slidably mounted on said yoke and brace bar, respectively, a straight edge finger, and means to mount said finger on said gauge arm at the outer end thereof in upright position and for lateral swinging movement about an axis perpendicular to the axis of said gauge arm, comprising an outer end section on said gauge arm hinged to said arm.
4. In apparatus for use in erecting a circular wall, a pole adapted to be arranged in upright position in the axis of said wall, a U-shaped yoke extending laterally from said pole and having ends rotatably and slidably mounted on said pole, an upright brace bar fixed to the yoke, a gauge arm adapted to extend horizontally from said yoke and having an inner end portion slidably mounted on said yoke and brace bar, respectively, a straight edge finger, and means to mount said finger on said gauge arm at the outer end thereof in upright position and for lateral swinging movement about an axis perpendicular to the axis of said gauge arm, comprising an outer end section on said gauge arm hinged to said arm, said finger being swingable on said section edgewise into different set positions.
